UNITED STATES PATENT OFFICE

152,081

DESIGN FOR A BRACELET OR SIMILAR ARTICLE

William W. Hobé, New York, N. Y.

Application September 21, 1948, Serial No. 148,681

Term of patent 3½ years

(Cl. D45—4)

To all whom it may concern:

Be it known that I, William W. Hobé, a citizen of the United States of America, residing in New York city, county of New York, and State of New York, have invented a new, original and ornamental Design for a Bracelet or Similar Article, of which the following is a specification, reference being had to the accompanying drawing, forming part thereof, wherein:

The units of the bracelet and their connecting links, as shown in dotted lines, are identical in appearance to the units and connecting links shown in solid lines, and are thus drawn for convenience of illustration.

I claim:

The ornamental design for a bracelet or similar article, substantially as shown and described.

WILLIAM W. HOBÉ.
